WO 2012144882 A1 10/2012

Primary Examiner — Ania Aman

(74) Attorney, Agent, or Firm — Meunier Carlin & Curfman LLC

(57) **CLAIM**

The ornamental design for a chimenea as shown and described.

DESCRIPTION

FIG. 1 is a perspective view of a chimenea stand showing a new design;

FIG. 2 is front view of the chimenea of FIG. 1;

FIG. 3 is a rear view of the chimenea of FIG. 1;

FIG. 4 is a left side view of the chimenea of FIG. 1;

FIG. 5 is a right side view of the chimenea of FIG. 1;

FIG. 6 is a top view of the chimenea of FIG. 1; and,

FIG. 7 is a bottom view of the chimenea of FIG. 1.

The broken line shown in the drawings are for the purpose of illustrating portions of the chimenea and form no part of the claimed design.

1 Claim, 7 Drawing Sheets(56)
